Primary Examiner — Omeed Agilee*(74) Attorney, Agent, or Firm* — Mintz, Levin, Cohn, Ferris, Glovsky and Popeo, P.C.; Zachary L. Terranova(57) **CLAIM**

The ornamental design for a microplate receiver frame, as shown and described.

DESCRIPTION

FIG. 1 is a top, front, and left side perspective view of a microplate receiver frame of our new design;

FIG. 2 is a bottom, rear, and right side perspective view thereof;

FIG. 3 is a top view thereof;

FIG. 4 is a bottom view thereof;

FIG. 5 is a left side view thereof;

FIG. 6 is a right side view thereof;

FIG. 7 is a rear view thereof; and,

FIG. 8 is a front view thereof.
